[57] CLAIM

The ornamental design for a cone shaped container, as shown and described.

DESCRIPTION

FIG. 1 is a front side perspective view of the cone shaped container of my claimed design;

FIG. 2 is a front side elevational view thereof, the back side elevational view being a mirror image thereof;

FIG. 3 is top end view thereof;

FIG. 4 is a bottom end view thereof;

FIG. 5 is a left side elevational view thereof, the right side elevational view being a mirror image thereof;

FIG. 6 is a cross sectional view along line 6—6 of FIG. 2; and,

FIG. 7 is cross sectional view along line 7—7 of FIG. 2.
